United States Patent

Des. 242,141

Patented Nov. 2, 1976

242,141

RIFLE

Leroy James Sullivan, 20861 Beachwood Lane,
Huntington Beach, Calif. 92646

Filed June 19, 1975, Ser. No. 588,458

Term of patent 14 years

Int. Cl. D22—01

U.S. Cl. D22—6

FIG. 1 is a side elevational view of a rifle showing my new design;
FIG. 2 is an elevational view of the other side thereof;
FIG. 3 is a top plan view thereof;
FIG. 4 is a bottom plan view thereof;
FIG. 5 is a front elevational view thereof; and
FIG. 6 is a rear elevational view thereof.

I claim:
The ornamental design for a rifle, as shown.
